CLAIM

The ornamental design for a tympanic membrane pressure equalization tube, as shown and described.

DESCRIPTION

FIG. 1 is a front perspective view of a tympanic membrane pressure equalization tube in accordance with the present invention showing our new design;

FIG. 2 is a top view thereof;

FIG. 3 is a side view thereof, the opposite side view being a mirror image thereof;

FIG. 4 is a bottom view thereof;

FIG. 5 is a side view thereof; and,

FIG. 6 is a side thereof.

The broken line showing of environment in the drawings is for illustrative purposes only and forms no part of the claimed design.

1 Claim, 3 Drawing Sheets
